UNITED STATES PATENT OFFICE.

MINNIE D. ARMSTRONG, OF DUNSMUIR, CALIFORNIA.

DESIGN FOR A BOOK END OR SIMILAR ARTICLE.

Application filed August 23, 1926. Serial No. 18,838. Term of patent 14 years.

To all whom it may concern:

Be it known that I, MINNIE D. ARMSTRONG, a citizen of the United States, residing at Dunsmuir, Siskiyou County, State of California, have invented a new, original, and ornamental Design for Book Ends or Similar Article, of which the following is a specification, reference being had to the accompanying drawing, forming part thereof.

I claim:

The ornamental design for a book end or similar article, as shown.

San Francisco, Cal., Aug. 17, 1926.

MINNIE D. ARMSTRONG.
